UNITED STATES PATENT OFFICE

FRANCIS TULLIUS FAY CARR, OF GLASGOW, SCOTLAND

GOLF CLUB

Application filed July 19, 1928, Serial No. 293,990, and in Great Britain August 18, 1927.

My invention relates to improvements in and connected with golf clubs, and particularly to what is known as "the putter" and resides in making the putter head of aluminium in a form resembling that of a putting cleek and with grooves, corrugations, or such like along the sole or base and similar corrugations or grooves along the striking face of the head.

- 10 The heads may be made in various lies, lofts, and weights and with straight or twisted necks or sockets to suit the various styles of players, the shaft being made of wood, metal or other suitable material.
- 15 In order that this invention may be properly understood and readily carried into effect, I have hereunto appended one sheet of drawings illustrating one form of golf club in accordance with my invention, of which

- 20 Figure 1 is an inverted plan.
Figure 2 is a perspective view.

Referring to the drawings, A is the putter head of aluminium which resembles that of a putting cleek and, as stated, may be made of different lies, lofts, and weights, the drawing showing one form only. B are the grooves, corrugations or such like on the sole or base C of the head A, and D are the grooves or corrugations along the striking face E of the head A. F is the shaft of any suitable metal or material.

The golf putter, made in accordance with my invention, permits of the player making a much freer and more confident stroke than he can risk with any existing putting club, and also gives the player greater control over the ball as regards distance.

It is specially designed for use on keen, fast or fiery greens, and the corrugated or grooved sole or base prevents the club from slipping when grounded on a glassy surface (and possibly moving the ball). The composition of the material combined with the design of the club have the effect of causing the ball to "bite" closely to the ground, a vital thing in putting.

I claim:

A putter for use in playing golf comprising a handle or shaft and a head connected to the lower end of said shaft, said head being

formed of an aluminum alloy and provided with a striking face having a series of ribs and grooves therein, and a sole substantially at right angles to said striking face, said sole being also provided with a series of ribs and grooves on the lower face thereof running at substantially right angles to the path of movement of the club.
